UNITED STATES PATENT OFFICE.

GOTTLOB FUEGEL, OF BROOKLYN, AND HERMAN SCHMID, OF KINGSTON, NEW YORK,
ASSIGNORS TO APOLLO MAGNETO CORPORATION, OF KINGSTON, NEW YORK, A COR-
PORATION OF DELAWARE.

CIRCUIT BREAKER FOR MAGNETOS.

Application filed March 3, 1920. Serial No. 363,014.

To all whom it may concern:

Be it known that we, GOTTLÖB FUEGEL and HERMAN SCHMID, who were formerly subjects of the German Empire, but who have severally renounced all allegiance to said Power and declared our intentions of becoming citizens of the United States, residing in Brooklyn, in the county of Kings and State of New York, and Kingston, in the county 5 of Ulster and State of New York, respectively, have invented certain new and useful Improvements in Circuit Breakers for Magnets, of which the following is a specification.

15 Our invention relates to an improvement in circuit makers and breakers; particularly circuit controllers or timers for magnets in the ignition systems of internal combustion engines.

20 The primary object of our invention is to provide a timer comprising but few parts, and so made that the timer can readily be assembled and dismounted for inspection or repairs; the various features being of such 25 a nature that the timer will work perfectly, while its liability to become worn or to get out of order is reduced to the smallest possible minimum.

A further object of our invention is to 30 provide a circuit breaking lever or interrupter element of such construction as will best serve our purposes when our invention is operated under practical conditions.

Other objects and advantages of our invention will appear from the following description, taken in connection with the accompanying drawings; and the novel features of our invention will be defined in the appended claims. This disclosure, of course, 35 is illustrative only and we may resort to other embodiments of our invention to the full extent indicated by the general meanings of the terms in which the claims are expressed.

40 On the drawings:—

Figure 1 is a front elevation of a support for the principal parts of the construction of our timer;

Figure 2 is a section taken on the line 2—2 of Figure 1;

Figure 3 is a side elevation of the support shown in Figure 1, viewed from the right;

Figure 4 is a view similar to Figure 2, showing the support with one of the contact-carrying members affixed in place;

Figure 5 is a section through the circuit-breaking lever or interrupter element of the timer carrying the movable electrode; and

Figure 6 is a front view in elevation of the timer complete.

The same numerals identify the same parts throughout.

Our timer comprises a support 1 which is in the form of a disc or circular plate of metal, and is adapted to be mounted to rotate with the armature of an ignition magneto, by being mounted on one end of the shaft thereof. To this support is movably secured a lever or interrupter element 2; which is fully shown in Figures 5 and 6; and 50 which is held in place by connecting it to a projection 3 on the support 1 near the circumference of the latter. The lever 2 carries a movable electrode or contact, which co-operates with a fixed contact carried by 55 a block 4. This block 4, as shown in Figures 4 and 6, is made fast to the support 1. The projection 3 is diametrically in line with the block 4 and the electrical connections will be such that when the electrode carried by the 60 lever 2 is held against the electrode carried by the block 4, the circuit of the armature will be closed. This block will be of brass or other metal.

The support 1, as indicated in Figures 1 and 3, is preferably made in one piece by casting it out of some suitable metal, such as brass. The projection 3 will be on one face; this face being the forward face of the timer; and on the rear or opposite face of the support 1 is a hollow integral boss or hub 5, which enables the support to be mounted upon the shaft of the armature of the magneto, which of course does not need to be shown or described herein. The projection 3 will have grooves or recesses in its

opposite ends, as indicated at 6 in Figure 3; the ends in question being shown as the upper and lower ends on Figure 1, and being, more properly speaking, the advance 5 end and the trailing end of the projection 1, with reference to the direction of rotation of the support; and the outer face of this projection, or that face which is nearest the rim of the support, will have a similar 10 groove or recess 7 illustrated in Figure 2. Both the grooves 6 and the groove 7 will have threaded holes 8 in the bottom of the same to enable the lever 2 to be secured to the projection 3.

15 On its rear face the support 1 will have an opening 9 to receive the ground brush of the timer; this opening being approximately in line with the projection 3; and diametrically opposite the opening 9, there 20 will be an opening 10 to receive the screw which fastens the block 4 to the support 1.

The lever or interrupter element of the timer is indicated in Figures 5 and 6, and it is shown as comprising a curved body approximately 25 semi-circular in shape, with reinforcing ribs 11 along both its lateral edges. At one end it is made a little thicker and provided with a threaded opening in which we screw small bolt 12. This bolt may be 30 inserted into the threaded opening from below, with reference to Figure 5, and to the head of this bolt, which is to be located on the inner or concave side of the lever, will be welded or affixed in any other manner, a 35 small piece of platinum or other substance. This contact point is indicated by the numeral 13 and it constitutes the movable electrode of our timer.

The ribs 11 increase in width from the 40 ends at which the bolt 12 is located towards the opposite end of the lever 2. At this opposite end of the lever is carried a U-shaped fastening device 14. This device 45 14 is secured to the lever by a rivet 15 and it receives between the arms thereof a friction block 16, which can be made of fibre or some other suitable insulating material. The rivet 15 engages the middle of the fastening device and the end of the lever between the ribs 11; and the friction block 50 16 is held in place by a rivet 17, which passes through both the block and the ribs 11; and by a similar rivet 17 which passes through the two arms of the device 14 and the block 55 16, at right angles to the first rivet. This last named rivet projects somewhat beyond one of the arms of the fastening device and secures thereto an angle piece 18; this angle piece being located at a slight distance from 60 the adjacent end of the lever 2.

The lever 12 is mounted on the support 1 by yieldable means, such as resilient leaf springs 19, which are arranged in sets; one set being riveted to the end of the lever

adjacent the bolt 12 and being secured to the 65 projection 3 at one extremity of the same; and the other set being secured to the opposite end of the lever 2 by placing them between the lever and the fastening device 14 and causing them to be engaged by the 70 rivet 15; whereby a single rivet secures the ends of these springs and the fastening device in place. The other ends of the second set of springs will of course be made fast 75 to the opposite end of the projection 3. The ends of these springs which engage the projection are placed in the grooves 6 and are held by suitable screws entering the threaded holes 8. We may of course use as many 80 springs in each set as circumstances require but in this case we show two leaf springs extending from the rivet 15 to the projection 3, and three extending from the other end of the lever to the projection 3. At 85 their ends which are joined to the lever, the springs of each set may be in contact with each other, but at the ends which are fastened to the projection 3 it is desirable that the springs be separated. We accordingly 90 insert between the springs at the projection 3 a number of shims 20 (Figure 5); these shims being perforated to let the binding screws go through them as the springs are affixed to the projections 3. Hence the electric current in passing through the electrode 13 to ground does not flow from one 95 spring to another between the lever 2 and the projection 3; but follows the line of each spring separately. Therefore sparking between the springs and rusting or oxidation 100 thereof are prevented.

The springs above described serve simply as carrying or mounting springs which unite the lever to the support 1. We may also employ another set of springs 21 which extend from the groove 7 of the projection 3 to the angle piece 18. These latter springs constitute an operating member, and serve primarily to hold the lever 2 in circuit-closing position. We have shown the springs 110 21 as being three in number, for example; two being fastened both to the projection 3 and the angle piece 18 by suitable screws; one arm of the angle piece extending out from the element 14 and having a threaded opening, indicated at 22 in Figure 5, to receive one of these screws; the other screw entering the hole 8 in the groove 7; and the ends of these two springs 21 at the projection 3 may be separated by shims for the 115 same reasons as the springs 20. The third spring of the operating set may be simply a reinforcing spring which extends from the projection 3 only about half way to the angle-piece 18. See Figure 6.

The support 1 may be recessed on its front face as indicated at 13 in Figures 1, 2, 3, 4 and 6, adjacent the face of the projec-

tion 3 opposite the groove 7; and in this recess we may place a flat plate of insulation 24 which prevents contact between the block 4 and the support 1. The plate 24 and the block 4 are held fast to the support by means of a screw 25 passing through the hole 10 and the block 4; and the hole at the rear of the support may have a shoulder to serve as a seat for an insulating washer or bushing 26 which keeps the shank and head of the screw 25 out of contact with the support 1. As indicated in Figure 4, the bushing 26 extends entirely through the support from back to front, piercing the insulation 24 and entering the back of the block 4 which is bored out around the hole for the screw 25 for that purpose. This screw will pass through the insulation 24 into a threaded opening in the block 4 and project slightly beyond the forward face of this block. The projecting end of the screw may be made of reduced diameter and the threads in block 4 need not extend all the way through it; so that after the screw 25 is made tight, the reduced end of the screw can be riveted over to bind the screw and block in place.

The block 4 will be long enough to extend across the opening through the boss 5, and between the opening through this boss and the screw 25 it will carry a transverse bolt 27. The head of this bolt will be located on the side of the block adjacent to the bolt 12, and it will have thereon a similar bit of platinum 28 or other substance to co-operate with the platinum 13. On the opposite face of the block 4 the screw 27 will receive a binding nut 29.

In line with the bore of the hub 5 the block 4 will have an opening to give passage to a bolt or pin which is screwed into the end of the shaft of the magneto and connected with the insulated extremity of the generating winding. The hub may also have a spline or key 30, formed by punching; which, when the support 1 is applied to the end of the hollow shaft of the armature, will engage a key way in said shaft and cause the support 1 to rotate with the armature without slipping.

The springs 21 will actuate the lever 2 so as to cause the electrode 13 to make contact with the electrode 28. In practice the lever 2 will be rotated by the support 1 on the inside of a ring, not shown, with cam portions or projections to engage the block 16, and whenever one of such cam portions comes into play, it moves the lever against the force of the springs to separate the platinum electrodes. The ends of the platinum electrodes 13 and 28 are provided with meeting surfaces of some extent; and a quick opening and closing of the electric circuit is always secured, and perfect operation always assured, even at very high speeds.

As usual, one end of the winding of the armature of the magneto, not shown, will be connected to ground through the body of the armature and the other will be joined to the pin which passes through the block 4 and hub 5 into the end of the hollow armature shaft to the winding. This pin will of course be out of contact with the metal of the support 1 and the current will flow through this pin, the block 4, the platinum electrode 28, the platinum electrode 13, the lever 2, and the support 1 to the magneto frame and ground. To secure a good ground connection the recess 9 may be provided with a carbon brush which will be engaged at its inner end by a coiled spring and pressed against the end of the metallic frame or housing of the magneto. Whenever electrodes 13 and 28 are separated the circuit of the primary winding of the armature is broken and high tension current is induced in the secondary, which gives a spark. The screw 27 can be adjusted when necessary; and should anything ever go wrong with the lever 2, it can be taken off at once by removing the screws which fasten the springs to the projection 3. In fact the whole timer construction is very simple and the number of constituent parts is few and there is little likelihood of their ever getting out of order or requiring attention. In case of accident or damage however, the parts are all accessible and any one requiring to be taken off for repair can be removed at once. The front end of the bore through the hub 5 is shouldered to receive an insulating washer 31, which goes through the insulation 24 and enters the rear of the block 4. See Figure 4. The pin which is applied to hold the timer on the shaft of the armature, will be of less diameter than the bore of the hub 5, and therefore its front end will be out of contact with everything except the block 4; and the bushing 31 serves to hold the block against movement around screw 25 as an axis.

The opposite face of the block 4 may be counterbored slightly around the ends of the threaded opening for the bolt or screw 27; as indicated in Figure 6. By counter-boring the block in this way the adjustment of the screw 27 is facilitated.

When the lever 2 moves to carry the electrodes 13 and 28 together and to separate same it does not rotate about any definite axis; but rather, as the springs yield, it moves bodily in the general direction of a diameter through the center of the support 1. This diameter will make an angle with the axis of the bolt 27; but the meeting faces of the electrodes 13 and 28 will always come together flat or squarely.

By increasing the width of the ribs 11 as they approach the block 16, the mass of the timer lever is made greater at the end where

1 this block is located. Hence the faster the support 1 rotates the more will centrifugal force act to reinforce the springs and hold the lever in circuit-closing position. This 5 fact, in conjunction with the circumstance above-mentioned that the meeting surfaces of the electrodes 13 and 28 always come together and separate squarely, ensures most efficient action; giving us an instantaneous 10 and complete closing of the circuit when the electrodes 13 and 28 touch each other, and ensuring that the circuit remains closed till it is desired to move the lever to break it; and then the breaking of the circuit is completed 15 just as quickly as the making of it. In other words, the electrodes 13 and 28 do not come together by meeting at their edges and then over their surfaces. Such a mode of operation would not produce either quick 20 making or quick breaking and the disadvantage thereof is avoided by the construction and mode of operation which we have just described.

With the parts shown in the position indicated in Figure 6, the direction of the rotation is to be taken as counter clockwise. If clockwise rotation is desired, all that has to be done is to remove the bolt 27 from the block 4 and replace it in such a position 25 that the electrode 28 will be below the block instead of above it as shown in Figure 6; and to disconnect the lever 2 by loosening the springs which hold it to the projection 3 and then to rotate this lever with the 30 springs 20 thereon about a horizontal axis to carry the block 16 above the block 4 in Figure 6 and the end with the screw 12 below the block 4. Then, by restressing the 35 springs to the projection 3, the necessary 40 reversal of parts is finished and operation in the reverse direction can take place.

The use of the springs 19 and 21 renders oil unnecessary.

We also wish to call attention here to the 45 fact that the use of springs enables us to dispense with a pivot for the lever 2. If a pivot had to be employed and the lever mounted thereon, this lever could not engage the pivot tightly enough to eliminate 50 movement of the lever in such a manner that it at times would not be perfectly parallel to the face of the support 1. In other words, in order to enable the lever to be moved to separate the electrodes 13 and 28, it would 55 have to be loose enough on its pivot, and this looseness might at times permit the lever to wabble; so that one of its ends would be closer to the support than the other; especially after the pivot becomes worn with 60 constant use. Hence the contacts 13 and 28 instead of meeting squarely over their entire faces to close the circuit, might sometimes touch only at one point adjacent their edges; whereas the contacts should both 65 separate and come together instantaneously over

the whole extent of their meeting faces. The springs make impossible such wabbling movement, and hold the lever always parallel to the support 1. In order to get best results, these springs must of course be of some breadth relative to their thickness and we may of course use as many of these springs as are required. The spring parts 19 attached to the two ends of the lever 11, and to the bearing or projection 3, can be termed operating or supporting springs; while the springs 21 can be regarded as supplemental springs for the purpose set forth. From one point of view, the two sets of springs 19 can be regarded as a single spring element, because they work the same as one spring would work if attached to the two ends of the lever 11 and bent around the bearing or projection 3, and attached to this bearing adjacent its middle.

Having described our invention what we believe to be new and desire to secure Letters Patent of the United States is:—

1. The combination of a support having a projection, a lever comprising a curved body, yieldable means secured to both ends of said lever and said projection to mount said lever, and a resilient operating member secured to said projection and to one end of said lever.

2. A support having a projection thereon, an interrupter element having a curved body disposed adjacent one face of said projection, yieldable means secured to the ends of said element and said projection for mounting said element in position, and a resilient member connected to said element and to the opposite face of said projection to operate said element.

3. The combination of a rotatable support having a projection on one face; an interrupter element comprising a curved body with reinforcing ribs along its lateral edges disposed in front of said support adjacent one side of said projection, yieldable means secured to the ends of said projection and to the ends of said element for holding the element in position, a U-shaped fastening device secured to one end of the element between the ribs, a block of suitable material in said device, an angle piece secured to said device, and a resilient operating member secured to said element and to the opposite face of said projection.

4. In a mechanical interrupter, a rigid interrupter lever, supporting spring parts supporting the lever for deflection from and to a normal position, and a supplemental spring continually resisting the deflection of the lever from said normal position.

5. In a mechanical interrupter, a rigid interrupter lever, supporting spring parts attached at both ends of the lever and supporting it for deflection from and to a normal position, and a supplemental spring at-

tached to the lever and continually resisting the deflection of the lever from said normal position.

6. In a mechanical interrupter, a rigid interrupter lever, a spring element attached to both ends of the lever, a bearing fastened to an intermediate part of said spring element to support the lever for deflection from and to a normal position and a supplemental

spring attached to the lever and continually resisting the deflection of the lever from said normal position.

In testimony whereof, we have signed our names to this specification this 20th day of February 1920.

GOTTLOB FUEGEL.
HERMAN SCHMID.
